UNITED STATES PATENT OFFICE

JAMES R. WATKINS, OF CHICAGO, ILLINOIS, ASSIGNOR, BY MESNE ASSIGNMENTS, TO CHICAGO MILL AND LUMBER COMPANY, OF CHICAGO, ILLINOIS, A CORPORATION OF DELAWARE

PACKING DEVICE

Application filed November 21, 1930. Serial No. 497,153.

This invention relates to packing devices and more particularly to a construction for safely and effectively packing for shipment articles of furniture having highly finished surfaces, such as radio and phonograph cabinets which require protection against marring. One object of the invention is to provide an easily assembled packing device of sturdy yet simple construction which can be cheaply and economically manufactured and, while affording a safe and effective packing construction, at the same time facilitates the packing operation.

A further object of the invention is to provide a frame to be inserted between the sides of a cabinet and the packing case in which it is shipped, which will hold said cabinet in spaced relation to the sides of the packing case and thus prevent marring.

Another object of the invention is to provide a frame or spacing member for use in packing highly finished cabinets which may be associated with one wall of a cabinet and which includes means for engaging a portion of the adjoining walls whereby the spacing member is held in place frictionally, requiring no securing means between the frame and the cabinet nor between the frame and the packing case in which the cabinet is shipped.

To these and other ends the invention resides in certain improvements and combinations of parts, all as will be hereinafter more fully described, the novel features being pointed out in the claims at the end of the specifications.

In the drawing:

Fig. 1 is a perspective view, showing the frames assembled on a radio cabinet which has been partly inserted into a packing case;

Fig. 2 is a sectional plan view taken on line 2-2 of Fig. 1; and

Fig. 3 is a perspective view of the spacing member removed from the packing case.

Similar reference numerals throughout the several views indicate the same parts.

The present invention provides a spacing frame for use in packing fine articles of furniture which must be protected in shipping, and is particularly adapted for use in packing radio cabinets of the type which has a door

or a removable panel in either the front or rear wall through which the radio receiving unit and loud speaker are inserted for installation.

The invention, as disclosed, comprises essentially a frame formed of a plurality of members secured together in such a manner as to space a side wall of a cabinet and its adjoining front and rear wall from the surrounding walls of a packing case, the frame also presenting abutment surfaces, suitably spaced apart and adapted to grip the front and rear sides of a cabinet, leaving only sufficient space between the frame and the cabinet for the insertion of suitable packing material to prevent marring.

Referring more particularly to the drawing, the numeral 12 designates the spacing frame as a whole. This frame comprises, in the present instance, two pairs of members, 14, 14 and 15, 15, which are preferably, but not necessarily, made of wood.

The members forming the frame 12 are of a length to correspond to the dimensions of the cabinet upon which they are to be assembled. An important feature of the invention, however, is to correlate the size of the packing case so that the spacing frame will substantially fit the inside of such packing case when the cabinet has been placed therein.

While the dimensions of the wood pieces may be varied within wide limits, it is preferable to use frame members having a greater width than thickness. The width of the frame members should be sufficient to safely space all of the trim of the cabinet from the walls of the packing case when the frame members are against the untrimmed portions of the cabinet.

The various members of the frame are preferably arranged as shown in Figs. 1 and 2, namely, one pair of members 14, 14, lie in the same plane and the other pair of members 15, 15, is secured on the same sides of said members 14, 14, adjacent the ends thereof and with their flat surfaces at right angles to the flat surfaces of the members 14, thus forming abutment surfaces on the inner side edges of the upright portions 14, 14 which

will engage, respectively, a portion of the front and rear sides of the cabinet.

In using the construction of the present invention, a packer will first make up a packing case 10, with one of its sides left off. The packer will then select a frame of the proper size and packing material 13 will be placed on the cabinet 11 so as to be between the frame and the sides of the cabinet. Any other suitable means for protecting the cabinet from the frame may be used, such as small felt disks or pads, glued to those surfaces of the frame which will come in contact with the cabinet.

15 The packer will then place the frame upon the cabinet, the relationship of the frame to the cabinet being such that when the packing material is in place the frame will frictionally engage or grip the front and rear faces of 20 the cabinet and thus hold the frame in place while the cabinet is being slid within the packing case. Any suitable means may be used to protect the top of the cabinet and, in the present instance, boards 16, 16, of suitable dimensions, are utilized. In order to prevent the boards from marring the top of the cabinet, additional pieces of packing material 13 are employed between the boards and the cabinet. After the frames have been 30 adjusted on both sides of the cabinet, it is then slid into the packing case with the outer side edges of the cross pieces 15, 15 touching or substantially touching the sides of the packing case.

35 Any suitable means may be employed for protecting the legs of the cabinet. A suitable arrangement for this purpose is disclosed in patent to C. W. Gerlach, No. 1,694,973, issued December 11, 1928. For simplicity of illustration the legs are merely shown as resting on the bottom of the packing case.

40 After the cabinet is in place within the packing case the pieces 16, 16 will preferably be inserted. While it is possible, of course, to assemble the pieces 16, 16 with the cabinet before it is slid into the case, it is generally easier to insert these pieces after the cabinet is in place.

45 After the cabinet has been inserted into the packing case, the case will be closed by nailing on its open side a rear wall, similar in form to the other walls of the case.

50 From the foregoing it is apparent that the finished surfaces of the cabinet are spaced from the walls of the packing case, the cabinet is held from rearward movement by the two frame members 14, 14 at the rear and by corresponding members at the front. The cabinet is spaced from each side of the packing case by means of the frame members 15, 15. It will be noted that the frame members 14, 14 serve the dual purpose of providing abutments for gripping the front and rear walls of the cabinet as well as to provide a means for maintaining the frame members

15, 15 in spaced relation. If desired, abutment means independent of the members 14, 14, can be employed.

55 This manner of packing a cabinet lends itself particularly well for use with radio cabinets designed to receive replaceable units, since it is only necessary to remove one wall of the packing case and then remove the usual panel at the rear of the cabinet (indicated in Fig. 1 at 17) so that access can be had to the interior thereof. In this way a distributor of radio sets may receive cabinets from the cabinet manufacturer and readily assemble in the cabinets the radio receiving units which he has received from a radio receiver unit manufacturer. After the unit has been secured in place within the cabinet the panel is replaced and the rear wall of the packing case is then again secured in place to enclose the cabinet. The cabinet, containing the radio receiving unit is then ready for shipment to the retailer.

60 Due to the fact that the abutment faces of the spacing frames terminate short of the edge of the panel 17 it is apparent that the frames need not be disturbed in any way while the panel is being removed and replaced.

65 When it is desired to unpack the case, either the front or back wall, as desired, is removed. The cabinet may then be slid outwardly from the packing case, without any possibility of damaging its finish. The outer side edges of the cross pieces 15, 15, will serve as a guiding means for the cabinet as it is being slid outwardly of the packing case.

70 The device of the present invention also lends itself particularly to systems of distribution of cabinets and receiving units in which the receiving units and cabinets are made at distant points and are shipped to a common point for assembly and further distribution to the retailer.

75 The word "cabinet" where used in this specification and in the claims appended hereto is intended to include any article such as furniture and similar objects having a surface which requires to be protected to prevent its being scratched or otherwise marred.

80 While the present description sets forth a preferred embodiment of the invention, numerous changes may be made in the construction without departing from the spirit of the invention, and it is therefore desired that the present embodiment be considered in all respects as illustrative and not restrictive, 115 reference being had to the appended claims rather than to the foregoing description to indicate the scope of the invention.

85 I claim:

90 A spacing frame for a cabinet adapted to space the cabinet from certain walls of a surrounding packing case, said packing device comprising spaced frame members having a cross-section of greater breadth than thickness and disposed in edgewise relation- 130

ship between the adjacent walls of the packing case and the cabinet, additional frame members also having a cross-section of greater breadth than thickness, said additional frame members being secured in flatwise relationship adjacent the ends of the first mentioned spaced frame members so that the edges of said last mentioned frame members abut respectively against the front and rear walls of

said cabinet whereby the frame is adapted to firmly grip the front and rear walls of the cabinet to maintain it in place thereon and to maintain the front and rear walls and a side wall of the cabinet spaced from the corresponding sides of the packing case.

Signed at Chicago, Illinois, this 18th day of November, 1930.

JAMES R. WATKINS.
